UNITED STATES PATENT OFFICE.

WILLIAM M. BECK, OF ELWOOD, INDIANA.

TRACK DEVICE FOR AUTOMATIC TRAIN CONTROL.

Application filed March 12, 1923. Serial No. 624,321.

To all whom it may concern:

Be it known that I, WILLIAM M. BECK, a citizen of the United States, residing at Elwood, in the county of Madison and State 5 of Indiana, have invented new and useful Improvements in Track Devices for Automatic Train Controls, of which the following is a specification.

This invention relates to track devices for 10 cooperation with suitable devices carried by a train to automatically stop the train in time to prevent collisions and damages.

The object of the invention is to provide 15 a trip-device that may be operatively connected with the wires or rods as the case may be, used in block and other signaling devices whereby the trip will be set to actuate a train device simultaneously with the setting of the sight-signal, or which may 20 be operated by its own mechanism, separate and distinct from any other.

A further object is to provide a trip that 25 will go automatically to a position for operating the train mechanism in the event that its operating wires or rods become accidentally broken or too loose.

Another object is to provide means for so 30 balancing the trip that its operation will require but a minimum of power, and the object also is to provide a simple, durable 35 and inexpensive device, and to amply protect it from interference by rain, snow and ice.

I accomplish the above and other objects 40 which will hereinafter appear, by the mechanism illustrated in the accompanying drawings, in which—

Fig. 1, is a top plan view of my trip-mechanism in unset or inoperative position. Fig. 40 2, is a side elevation and vertical section taken on the line 2—2 of Fig. 1. This view shows the raised position of the trip in dotted lines. Fig. 3, is a fragment in side elevation of the mechanism of Fig. 1 in raised position of the trip. Fig. 4, is a plan view of two railroad tracks crossing each other, and showing my invention installed along one of the tracks for operation with and by a derailing and signaling mechanism such as is now in common use. Fig. 5, is a side elevation showing the trip in raised 45 position about to be contacted by the trip-member of a train device, and showing the trip-operative mechanism correspondingly arranged and partly hid by a protective housing. Fig. 6, is a turnbuckle for tightening wires and rods, and Fig. 7 is a plan view

of a railway track and switch with my invention so applied as to be moved by the opening of the switch in position for operating the train device. 60

Like characters of reference indicate like parts in the several views of the drawings.

Referring to Fig. 4 of the drawings which shows two tracks crossing each other at right angles, 8 are the track rails, and 9 the cross-ties of both tracks. Near their crossing is a signal-tower 10 and while the signaling and the train stopping mechanism is duplicated in practice for both tracks, I have only shown it for one of them, but desire it to be 70 understood that the same mechanism is applied in practice to both tracks. A derailing mechanism 11 of any suitable construction, such as that now in common use, is operated from the signal-tower by wires 12 75 and 13 (or rods) actuating through suitably pivoted levers at 14, and said wires are continued to a near-by "home signal" 15 and thence to a distant signal 16, all of which are of any usual or suitable construction, 80 with which railroads in many States are now required by law to be equipped. These, however, are sometimes overlooked by the train-men, and should the engineer neglect a distant signal my track-device is preferably placed between it and the derailing device far enough from the latter to stop 85 the train before the train is derailed.

This device comprises a head 17 resembling a gable-roof in form, one or the other of the two oppositely sloping sides of which will be contacted by a trip 18 carried by a passing train, when the head is moved into the path of the trip 18. Which one of the sloping sides is contacted will 90 depend upon the direction of travel of the train and the said sides will be elongated in a direction transversely of the track to prevent the train-trip missing the head because of variations in position of the trip 95 by inaccurate original placing or caused by accident or the variable lateral movement or swing of the train. 100

The head 17 has a stem-plate 19 that makes a sliding fit between a pair of parallel rigidly-held plates 20, 20. The said plates are preferably forged or cast integrally with a base-plate 21 which base-plate has integral flanges 22 and 23 that are parallel with the plates 20 and that are bolted to 110 adjacent sides of a pair of ties 24 and 25. Long enough ties are selected here to extend

beyond the rails 8 sufficiently far to support the device at the right distance away from said rails. Fillet flanges 26 are preferably formed between the plates 20 and their respective flanges 22 and 23 to brace and strengthen the structure.

The flange 23 has a journal-box 27 in which a rock-shaft 28 is mounted. This shaft 28 is supported by an additional box 29 bolted to the tie 25, and mounted in a fixed manner, here shown as splined on the shaft 28 are the two arms 30 and 31. These arms are parallel to each other and have longitudinal slots 32 near their outer ends through which pins 33 are passed. The pins 33 have heads to keep the pins from being accidentally withdrawn from the slot and their stems are seated in the respective ends of the plate 19, whereby, by rocking shaft 28, the plate 19, and consequently its head 17, will be moved, within the limits permitted by the guide-plates 20, 20. A series of holes 34 are provided for corresponding adjustment of the pins 33 in the plate 19 by which adjustment the height to which the head may be raised is regulated.

The outer end of the rock-shaft 28 carries a cross-arm 35 which has end-holes through which connections are so made with the respective wires 12 and 13 that the cross-arm is moved to rock the shaft 28 by the pull delivered through said wires.

An arm 36, fixed on the outer end of the shaft 28, has a weight 37 slidably adjustable on it and retained in a given position by a set-screw 39. By moving the weight the head may be so nearly balanced as to require only a small pull on the wires 12 and 13 to raise it, and preferably still so much overweighted that the weight 37 will automatically raise the head 17 and hold it in raised position in case of an accidental breaking of the wires. This will insure safety and also call attention to the broken wires.

In the operation of my invention, the wires 12 and 13 will be actuated by the man in the signal-tower in setting the block signals and the usual safety mechanism, and the movement of said wires acting on the cross-arm 35 (to which the wires are attached) rocks the shaft 28 in a direction to raise the head 17 to the position shown in full lines in Fig. 5, and in dotted lines in Fig. 2. The wires 12 and 13 are kept taut by turnbuckles 40. A reverse movement of the control-lever by the man at the signal-tower will lower the head 17.

The plate 19 and its guides 20 and the arms 30 and 31 are protected from rain and snow by a sheet metal housing 41, the roof of which has two angular raised portions 42 each terminating with a flange that is secured to one of the plates 20. Flange extensions 43 rest upon and are nailed to the

tops of the respective ties. Sides 44 make a tight fit against the base-plate 21 and flanges 22 and 23 and any liquid that may enter the closure thus made is drained out through a vent-cock 45 (Fig. 5) that has only discharge in an outward direction and keeps the closure drained of water and secure against interference in operation of the parts due to freezing.

In the modification shown in Fig. 7 the above-described track-device is operated by wires 46 and 47 attached to cross-arms that are connected by rods with the usual switch-lever 48 operated by a manually moved arm 49. When the switch is open for a train to take it and the train fails to slow down properly my track-device, set at a suitable distance away, brings the train to a stop before it reaches the switch.

My invention may be located on either side of a track outside of the rails or between the rails, and it may be set directly on the ties or elevated, and it may be modified in so many ways in form and dimensions that I do not desire to be held strictly to the showing here made, or any more than is required by the appended claims.

I claim:

1. In a device for the purposes specified, a head to contact with a train-member, a rock-shaft having one or more arms, means comprising a pivot for each arm connecting same with the head, manually operated means for rocking the shaft to move the head into the path of the train-member and adjustable means for varying the projection of the head into the path of the train-device.

2. In a device for the purposes specified, the combination with a train-device of an elongated gable-shaped head having its gable-end toward the railroad track, an extension in the opposite direction from the convergence of the gable, a rock-shaft, means connecting the shaft and head extension to move the head in and out of the path of the train-device, means for rocking the shaft and adjustable means for varying the projection of the head into the path of the train-device.

3. In a device for the purposes specified, the combination with a train-device of a head with oppositely sloping sides, a head extension, a rock-shaft, arms carried by the shaft, means connecting the head extension with the arms to reciprocate the head when the shaft is rocked, means comprising an adjustable weight for counterbalancing the head, and means for rocking the shaft.

4. In a device for the purposes specified, the combination with a train-device, of a head, a stem, a rock-shaft, an arm or arms carried by the shaft each arm having a longitudinal slot, a pivot pin in the stem passing through each arm slot, and manually

operated means for rocking the shaft and adjustable means for varying the projection of the head into the path of the train-device.

5. In a device for the purposes specified, a head, a stem, guides for the stem, a rock-shaft having one or more arms, means connecting the latter with the stem to reciprocate the stem and head when the shaft is 10 rocked, manually operative means for rocking the shaft and automatic means for moving the shaft to position in the path of a train-device when the manual means is broken and inoperative.
15. 6. In a device for the purposes specified, the combination with a train-device, of a head, a stem, guides for the stem, a rock-shaft, means connecting the rock-shaft with the stem to raise and lower the head in the 20 guides by the rocking of the shaft and adjustable means on the shaft comprising a weight for counter-balancing the weight of the head and stem, and means for rocking the shaft.
25. 7. In a device for the purposes specified, the combination with a train-device, of a head, a stem, guides for the stem, a rock-shaft, one or more arms on the rock-shaft having longitudinal slots, pivot pins carried by the stem and entering the slots in the arms, manually operated means for rocking the shaft, and an arm on the shaft hav-

ing an adjustable weight thereon to counter-balance the head and stem.

8. In a device for the purposes specified, a head having oppositely sloping sides, said sides being at right angles to a railroad track by which the device is placed and said head having undercut recesses under each sloping side, means for guiding the head, means for reciprocating the head on said guides, and a housing under the head to protect the guides and reciprocating means from rain and snow, said housing having an extension entering the undercuts in the head 45 in the retracted position of the head.

9. In a device for the purposes specified, the combination with a train-device of a head with oppositely sloping sides, said head being elongated in directions opposite 50 to the slope of its sides, a stem integral with the head, guides receiving the stem with a close moving fit, a rock-shaft, one or more arms on the rock-shaft, means connecting the arms with the stem of the head to reciprocate the stem and head and move the head in and out of the path of the train-device when the shaft is rocked, adjustable means for varying the projection of the 55 head into the path of the train-device, and means for rocking the shaft.

Signed at Indianapolis, Indiana, this 10th day of March, 1923.

WILLIAM M. BECK.
